UNITED STATES PATENT OFFICE.

JOHN H. JOHNSON, OF CHICAGO, ILLINOIS, ASSIGNOR TO FEDERAL-HUBER COMPANY,
OF CHICAGO, ILLINOIS, A CORPORATION OF ILLINOIS.

VALVE.

1,241,519.

Specification of Letters Patent. Patented Oct. 2, 1917.

Application filed March 24, 1913. Serial No. 756,293.

To all whom it may concern:

Be it known that I, JOHN H. JOHNSON, a citizen of the United States, residing at Chicago, in the county of Cook and State 5 of Illinois, have invented new and useful Improvements in Valves, of which the following is a specification.

It is the object of the present invention to provide a valve suitable for use in faucets, 10 ball cocks and the like and having special means for protecting against stoppage and injury to the valve when first installed and also having its parts so shaped and related as to be easily adjustable to different water 15 pressures, these parts also being so shaped that hammering is in large measure prevented and reliable and efficient operation insured.

When faucets and stop-cocks for water 20 closets are first installed in new buildings, they are subjected to severe treatment, owing to the action of steel and iron chips, rust and red lead in the water pipes, for when the water is first turned on, this dirt comes 25 through to the valve and is very likely to lodge on the valve seat, thereby preventing the valve from closing and making it necessary for a plumber to detach the fixture and remove the objections. In new buildings, 30 these stoppages are so frequent that faucets have to be taken off repeatedly, sometimes several times a day, with the result that when the building is completed and ready 35 for occupancy, the faucets have been badly damaged and marked up by the plumbers' wrenches, if not destroyed entirely.

According to the present invention, the 40 valve seat is protected from foreign matter and the faucet or other structure, of which the valve is a part, is so constructed that a heavy collection of sediment in the pipes can be removed without injury to the faucet.

In the drawings forming a part of the present specification,

45 Figure 1 is a sectional elevation through a faucet embodying the novel features of the present invention.

Fig. 2 is a perspective view of the valve and valve stem.

50 Fig. 3 is a perspective view of the valve spring and its perforated plate.

In the embodiment illustrated in the drawings, the valve stem 1 is in the form of a straight rod unthreaded at its upper end 55 and bearing at its lower end a shoulder 2

against which is clamped a packing ring 3 supported within a cap 4 which is threaded on to the lower end of rod 1. The lower part of cap 4 extends downward as a lug 5, flattened on each side to serve as wrench 60 seats. This lug 5 normally extends down into the upper end of a helically coiled spring 6, which carries on its lower end and preferably soldered thereto, a perforated disk 7. This disk normally fits on a shoulder 65 in the base casting 8 of the faucet or other structure, of which the valve is a part and serves as a strainer to hold back any iron chips or flakes and any large pieces of red lead or the like.

The upper edge of casting 8 is provided 70 with a threaded flange 9 and a nut 10 engages therewith and has its upper edge cupped inward to form an annular flange 11.

The valve seat of the embodiment here 75 illustrated is part of a cup member 12, which has its outer wall tapered, as shown, to fit within the flange 9 of the base casting 8. The inner diameter of this cup member 12 is only slightly larger than the outer diameter of the cap 4, say a thirty-second of an inch on each side, or with just enough space to give a suitable water-way for the particular water pressure under which the faucet 80 is to work. For unusually high pressures, such as are encountered on the lower floor 85 of tall buildings, a closer fit may be provided between cap 4 and cup 12 to cut down the pressure of water delivered at the spout of the faucet. An annular rib 13 carried at the 90 base of the cup is positioned to contact with the packing ring 3, thereby forming a water-tight seal under the combined action of spring 6 and the water pressure on the lower face of the cap 4. The central outlet 14 of 95 the cup member 12 is so nearly the same diameter as shoulder 2 on the valve stem, that the latter enters the outlet 14 with a snug fit.

The main casting 15 of the faucet is 100 threaded to the upper end of the cupped member and together with that member forms a chamber, in which the flange 11 of nut 10 may freely turn around when that nut is being unscrewed from the base member 8. This main casting may have a partition 16 serving to guide the valve stem 1 and the upper portions of the faucet, including the cap 17 and the cam mechanism 18, 105 may be of usual construction, the latter be- 110

ing provided with a socket for receiving the upper plain end of valve stem 1 and being actuated by a suitable handle 19 to force that valve stem downward when water is to be drawn off through the faucet.

- The downward movement of the valve stem 1 will carry cap 4 and its packing ring 3 downward in cup member 12 far enough to permit ready flow of water upward 10 through the perforated plate 7 and past the valve outward to the discharge spout. Any coarse sediment carried in the water will be caught by the perforated plate 7 and cannot get through to damage the valve seat. 15 Should a large particle of sediment be thrown violently into contact with the strainer-plate 7, the latter will yield under the influence of the spring so as to prevent damage to the strainer. When the handle 19 is released, the water pressure acting in conjunction with the spring 6 will lift the valve upward toward its seat, but the shut-off will not occur instantly, because of the back pressure offered to the valve by the water still 20 in the cup member 12 and its outlet 14. As the valve enters the cup 12 the water then in the valve will check further movements momentarily, or until the water has succeeded 25 in escaping out of the path of the closing valve.

Because of its fit in the outlet 14, the projection 2 also serves in checking the upward movement of the valve and assists in protecting the mechanism from hammering 30 when the valve closes.

With the structure here disclosed, even though the dirt in the pipes of the new building may interfere with the faucet, as by clogging plate 7 so that water cannot be 35 drawn off, this foreign matter, including the iron chips will not get in on the valve seat and will not prevent the valve from closing. To clean the faucet out, under these conditions, it is only necessary to shut off the

water supply, unscrew nut 10, then lift off 45 from the base member 8, all of the structure, including coiled spring 6 and its attached perforated disk 7, whereupon the valve can be pulled down out of the main casting 15 for inspection and repair. If desired, the 50 faucet can be put back without its valve and spring and the water then turned on to blow the sediment out through the spout of the faucet, after which the parts may be re-assembled and installed as before. Through- 55 out all these operations of cleaning the faucet, nut 10 is the only part that need be unscrewed and this is large and easily manipulated.

Although the specific embodiment illustrated in the drawings is a faucet, I contemplate using this same valve structure in ball cocks and other water controlling devices and I contemplate changes in the details of structure and in the arrangement of 60 parts within the scope of the appended claim.

I claim:

The combination of a pair of detachably connected conduits, one of said conduits having a valve seat and a valve therefor, the other conduit having an internal shoulder, a movable strainer in said other conduit and against the shoulder, and a spring disposed 70 between and exerting pressure in opposite 75 directions against the strainer and the valve to yieldably maintain the strainer and the valve in their normal positions, the strainer being attached to the spring and removable therewith.

In witness whereof, I hereunto subscribe my name to this specification in the presence of two witnesses.

JOHN H. JOHNSON.
